METAL-TWISTING MECHANISM.

1,415,502.

Specification of Letters Patent. Patented May 9, 1922.

Application filed May 15, 1920. Serial No. 381,650.

To all whom it may concern:

Be it known that I, WILLIAM J. YOUNG, a citizen of the United States, and resident of Rochester, in the county of Monroe and State of New York, have invented certain new and useful Improvements in Metal-Twisting Mechanisms, of which the following is a specification.

The present invention relates to a metal twisting mechanism and more particularly to the type in which a strip of metal is twisted between its ends, an object of this invention being to provide a simple and inexpensive construction which may be readily placed in a press to be operated by the latter. Still another object of the invention is to provide an improved twisting mechanism which will twist one portion of a metal strip to a position at right angles to portions on opposite sides thereof so that the said first named portion has its plane lying substantially in a plane with one edge of the portions lying on opposite sides thereof.

To these and other ends the invention consists of certain parts and combinations of parts, all of which will be hereinafter described, the novel features being pointed out in the appended claims.

In the drawings:

Fig. 1 is a plan view of a machine constructed in accordance with this invention;

Figs. 2 and 3 are plan views at right angles to each other showing a metal strip twisted in accordance with this invention;

Fig. 4 is an end view of the machine arranged in a press;

Fig. 5 is a section through the machine on the line 5—5, Fig. 1, showing the parts arranged in the press, the dotted lines illustrating the position to which the movable die is shifted by the press; and

Fig. 6 is a plan view of one of the lower twisting dies.

Referring more particularly to the drawings, 1 indicates a base plate which supports, in this instance, two spaced clamps for a metal strip 2 so that a portion between the clamps may be twisted. Each of these clamps embodies a fixed jaw 3 and a movable jaw 4. Each fixed jaw has a block 10^a secured thereto and provided with four shoulders or abutments 10^b any one of which may be brought into engagement with the upper edge of the strip, the different abut-

ments being provided to accommodate strips 55 of different widths without changing the dies. The movable jaw is moved through a screw 5, which is mounted to turn in an upward extension 6 formed integrally with the base 7 from which the stationary jaw 60 projects. A hand wheel 8 is provided on the screw for moving the movable jaw toward and from the fixed or stationary jaw 3. In order to accommodate strips 2 of different lengths, the base plate 1 is provided 65 with two series of openings 9 extending in parallel relation throughout the length of the base plate and adapted to receive bolts 10 carried by the clamping devices in order to secure said clamping devices at different 70 distances from each other on the base plate, the rear bolts also being utilized for holding the blocks 10^a to the stationary jaws 3.

Arranged to operate between the two clamping devices upon the strip 2 is a twisting mechanism comprising, in this instance, two separated twisting devices, each consisting of a pair of dies, the members of each pair operating upon opposite edges of the strip 2. One of these dies indicated at 11, is 80 preferably in the form of a plate adjustably mounted upon the base 1 as by being held thereto by screws 12 engageable in the series of openings 13 extending longitudinally of the base and permitting the positioning of the plate 11 at different points on the base 1. This die plate 11 preferably has a deflecting face 14 formed by concaving the upper surface, the front edge of this concave lying substantially under the 85 lower edge of the strip 2 before the latter is twisted. The other twisting die is preferably in the form of a member 15 pivoted at 16 to a frame 17 which is adjustable longitudinally of the base 1 preferably by providing the base 1 with a longitudinally extending groove 18 and with a longitudinally extending series of bolt openings 19, the frame 17 having a rib 20 on its under side operating in the groove 18 and said frame 100 carrying also bolts 21 engageable within the openings 19 to secure the frame 17 in its adjusted position. The movable or pivoted die 15 may be normally held in a raised position by a spring 15^a secured to the die and 105 to the frame 17 and has a deflecting surface 22 formed by one face of a hardened plate 23. The plane of this surface 22 is such

that, as the die member 15 swings about its axis 16, the surface moves angularly with reference to the stationary die 11. This deflecting surface 22 will shift the upper edge 5 of the strip outwardly or in one direction, while the deflecting surface 14, which engages the lower edge of the strip 2, will shift such edge inwardly or in the opposite direction. The axis 16 as well as the surface 22 are arranged so that eventually the 10 surface 22, while at the first part of its twisting action being arranged at an angle other than a right angle to the plane of the stationary die 11, will eventually move into 15 parallel relation with said die so that the portion of the strip 2 engaged by the twisting dies will be at right angles to the end portions and substantially in the plane with the lower edge of the end portions. In order 20 to draw the top edge of the flat strip rearwardly to the plane of the end portions, a shoulder or abutment 24 is provided at the outer end of the deflecting surface 22 and with this shoulder or abutment the upper 25 edge of the strip will engage after the strip has been partially twisted. After such engagement and during the continued movement of the upper die 15, the twisted portion of the strip will be shoved rearwardly 30 so that the lower edge of the strip will travel on the concave deflecting surface 14 and eventually the twisted portion of the strip will lie horizontally with its top edge in a plane with the vertically arranged end portions 35 and also in a plane with the lower edges of the end portions as shown in dotted lines in Fig. 5. For the purpose of permitting the shoulder 24 to be moved below the upper face of the stationary die 11, said 40 shoulder is narrower in width than the die member 15 and is adapted to be received in a notch 28 formed in the front edge of the die member 11. A shoulder in the form of a pin 29 may be provided for engagement 45 with the lower edge of the strip to prevent outward movement of the latter.

The mechanism as a whole is, in this instance, designed for use in connection with a metal press and to this end, its bottom 50 plate is bolted upon the stationary wall 25 of the press while the pivoted dies 15 are adapted for engagement by the movable plunger 26 of the press, each die having a hardened metal insert 27 projecting from its 55 upper side for engagement with the movable press member 26.

The operation of the invention will be understood from the foregoing description, but it may be summarized as follows:

60 A strip 2, preferably cold, although it may be hot, is clamped at opposite ends in the two spaced clamping devices after the latter have been adjusted to correspond to the twist to be made in the strip. The two 65 twisting devices are also adjusted on the

base frame to correspond to this twist, the upper dies 15 having their deflecting surfaces lying in engagement with the upper edge of the strip and the lower edge of the strip resting upon the lower dies 11 adjacent the forward portion of the concave deflecting surface 14. The machine as a whole is then inserted in a power press, being bolted to the base of the press, and the plunger 26 of the press is operated. The dies 15, 70 75 first through their deflecting surfaces 22, shift the central portion of the strip outwardly until the top edge of the central portion engages the shoulders 24. Thereafter the shoulders in connection with the surfaces 22 act on the central portion of the strip to cause such portion to assume a horizontal position, the lower edge of the strip being guided in its rearward movement by the concave deflecting surfaces 14. Eventually, the central portion of the strip assumes a position at right angles to the end portions, the top edge of the twisted portion being brought substantially to the plane of the front faces and lower edges of the 80 vertical or clamped end portions of the strip. 85

From the foregoing it will be seen that there has been provided a metal twisting mechanism which is simple in operation and effectively twists an intermediate portion of a metal strip to a position at right angles to end portions of such strip. This is effected by two die members, one of which shifts one edge of the strip in one direction while the other deflects the other edge of the strip in the opposite direction. One of these die members is stationary and has a curved deflecting portion, and the other is movable and has a straight deflecting face which engages the opposite edge at an angle other than at right angles to the plane of the strip, and during the twisting shifts to a position at right angles, an abutment being provided which shifts the edge toward the plane of the strip also during the twisting. 100 105 110 115

What I claim as my invention and desire to secure by Letters Patent is:

1. A machine for twisting flat metal strips comprising a pair of spaced clamps by which the strip is held, and a twisting mechanism operating between the clamps and embodying means coöperating with opposite edges of the strip to move a portion of one edge laterally out of line with those portions held by the clamps and a portion of the inner edge into alinement with the portions of the first named edge held by the clamp. 120

2. A machine for twisting flat metal strips comprising a pair of spaced clamps by which the strip is held, and a twisting mechanism operating between the clamps and embodying two dies cooperating with opposite edges of the strip to move a portion of one edge laterally out of line with those portions held 125 130

by the clamps and a portion of the other edge into alignment with the portions of the first named edge held by the clamps.

3. A machine for twisting flat metal strips comprising a pair of spaced clamps by which the strip is held, and a pair of twisting dies for cooperating with opposite edges of the strip, one of said dies having a face deflecting a portion of one edge of the strip in one direction out of line with the portions of such edge held by the clamps, and the other having a face deflecting a portion of the other edge of the strip substantially in a line with the portions of the first named edge held by the clamps.

4. A machine for twisting flat metal strips comprising a pair of spaced clamps by which the strip is held, and a pair of twisting dies for cooperating with opposite edges of the strip, one of said dies being stationary and having a face for deflecting a portion of one edge of the strip in one direction out of line with the portions of such edge held by the clamps, and the other being movable and having a face for deflecting a portion of the other edge of the strip in the other direction substantially in a line with the portions of the first named edge held by the clamps.

5. A machine for twisting flat metal strips comprising a pair of spaced clamps by which a strip is held, and a pair of twisting dies cooperating with the strip between the clamps, one of said dies being stationary and having a face for deflecting a portion of one edge of the strip in one direction out of line with the portions of such edge held by the clamps, and the other of said dies being movable and having a deflected face shifting angularly with reference to its plane to shift a portion of the opposite edge of the strip in the opposite direction substantially in a line with the portions of the first named edge held by the clamps.

6. A machine for twisting flat metal strips comprising a pair of spaced clamps by which a strip is held, and a pair of twisting dies for cooperating with the strip between the clamps, one of said dies being stationary and having the plane of its work face substantially at right angles to the original plane of the strip, the said die deflecting a portion of one edge of the strip in one direction out of line with the portions of such edge held by the clamps, and the other of said dies being movable and having a deflecting face engaging the opposite edge of the strip at an angle other than at right angles to the plane of the strip, said face being movable angularly to assume a position at right angles to the original plane of the strip and to shift a portion of the other edge of the strip substantially in a line with the portions of the first named edge held by the clamps.

7. A machine for twisting flat metal strips comprising a pair of spaced clamps by which a strip is held, and a pair of twisting dies for cooperation with opposite edges of the strip between the clamps, one of said dies being stationary and having a concaved deflecting face for deflecting one edge of the strip in one direction and the other of said dies being movable and having a deflecting face for shifting the opposite edge of the strip in the opposite direction, said last named deflecting face having its plane, when first engaging the strip, at an angle other than a right angle to the original plane of the strip, said deflecting face being movable angularly to assume finally a position at right angles to the original plane of the strip.

8. A machine for twisting flat metal strips comprising a pair of spaced clamps by which the strip is held, and a pair of twisting dies for co-operating with the strip between the clamps, one of which is stationary and has a concave face over which one edge of the strip shifts laterally out of the plane of the edge portions held by the clamps, and the other of which is movable for shifting said first mentioned edge over the concave face and deflecting the opposite edge of the strip in the opposite direction to the plane of the portions of the first mentioned edge held by the clamps.

9. A machine for twisting flat metal strips comprising a pair of spaced clamps by which the strip is held, and a pair of twisting dies for cooperating with opposite edges of a strip held between the clamps, one of said dies being stationary and having a face over which an edge of the strip shifts to deflect such edge of the strip in one direction, and the other of said dies being pivoted to turn about an axis parallel with the strip and having a face shifting said first-mentioned edge over the face and deflecting the strip in the opposite direction to the plane of the portions of the other edge held by the clamps.

10. A machine for twisting flat metal strips comprising a pair of spaced clamps by which the strip is held, a pair of twisting dies for cooperating with opposite edges of a strip held by the clamps, one of said dies being stationary and having a face for deflecting one edge of the strip in one direction and the other of said dies having a deflecting face for deflecting the opposite edge of the strip in the opposite direction, said last mentioned deflecting face engaging its edge in a plane at an angle other than at right angles to the original plane of said strip, said face being mounted to move angularly during the twisting to a position at right angles to the original plane of the strip, and an abutment carried by the movable die to cooperate with the adjacent edge

of the strip in order to shift said edge toward the original plane of the strip during the twisting.

11. A machine for twisting flat metal strips comprising a pair of spaced clamps by which the strip is held, and a pair of twisting dies for cooperating with the strip held by the clamps, one of said dies being stationary and having a deflecting face over which the cooperating strip edge shifts laterally out of the plane of the edge portions held by the clamps and the other of said dies being pivotally mounted and having a deflecting face arranged to shift its cooperating strip edge in the opposite direction, said pivotally mounted die also having an abutment for cooperating with the adjacent strip edge in order to shift said edge to the plane of the portions of the other edge held by the clamps.

12. A machine for twisting flat metal strips comprising a pair of clamps by which the strip is held, a pair of twisting dies cooperating with the strip held by said clamps, one of said dies being stationary and having a concave face for deflecting one edge of the strip in one direction, and the other of said dies being pivoted and having a flat deflecting face the plane of which, when first engaged the opposite edge of the strip, lies at an angle other than a right angle to the original plane of the strip, said plane of the deflecting face of the pivoted die moving during the twisting to a plane substantially at right angles to the original plane of the strip.

13. A machine for twisting flat metal strips comprising a pair of spaced clamps by which the strip is held, a pair of twisting dies cooperating with a strip held by said clamps, one of said dies being stationary and having a concave face for deflecting one

edge of the strip in one direction, and the other of said dies being pivoted and having a flat deflecting face, the plane of which 45 when first engaging the opposite edge of the strip, lies at an angle other than a right angle to the original plane of the strip, said plane of the deflecting face of the pivoted die moving during the twisting to a plane substantially at right angles to the original plane of the strip, and an abutment on said pivoted die cooperating with the adjacent edge of the strip to shift said edge toward the original plane of the strip as the strip 55 is twisted at right angles to its original plane.

14. A machine for twisting flat metal strips comprising a pair of spaced clamps by which the metal strip is held, and a pair 60 of twisting dies for cooperating with opposite edges of the strip between said clamps, one of said dies being stationary and having a face for deflecting one edge of the strip in one direction, and the other of said dies having portions for deflecting the opposite edge of the strip in the opposite direction and for moving said edge toward the original plane of the strip.

15. A machine for twisting flat metal 70 strips comprising a base plate, two clamps relatively adjustable on said base plate, and two twisting devices adjustable relatively to each other and to the clamps on said base plate and each comprising a stationary die having 75 a surface over which one edge of a strip shifts laterally out of the plane of the edge portions held by the clamps, and a movable die for deflecting the opposite edge of the strip in the opposite direction to the plane 80 of the portions of the other edge held by the clamps.

WILLIAM J. YOUNG.
